COMBINED RADIO AND TELEVISION RECEIVER

Osamu Sugihara, Yasunobu Nakamura, Tadashi Sumino,
Kazuhiro Ueda, Makoto Terauchi, and Kiyoshi Suzuki,
Osaka, Japan, assignors to Matsushita Electric Industrial Co., Ltd., Kadoma City, Osaka, Japan

Filed Dec. 17, 1971, Ser. No. 209,495

Claims priority, application Japan June 18, 1971

Term of patent 14 years

Int. Cl. D14—03

U.S. Cl. D56—4 D

FIG. 1

FIG. 2

FIG. 3

FIG. 4

FIG. 1 is a front perspective view of a combined radio and television receiver showing our new design.

FIG. 2 is a rear perspective view thereof showing television receiver in retracted position.

FIG. 3 is a left side elevational view thereof, and FIG. 4 is a bottom perspective view thereof.

Portions of FIGS. 1, 2 and 3 are stippled to indicate contrast in appearance.

We claim:

The ornamental design for a combined radio and television receiver, as shown and described.
